FLASH-CARD TEACHING APPARATUS

Robert N. Kharasch, 7300 Burdet Court, Bethesda, Md.

Filed June 22, 1961, Ser. No. 65,694

Term of patent 14 years

(Cl. D25—1)

FIG. 1

FIG. 2

FIG. 3

FIG. 4

FIG. 5

FIG. 1 is a perspective view of the flash-card teaching apparatus showing my new design;

FIG. 2 is a top plan view of the flash-card teaching apparatus;

FIG. 3 is a side elevation of the flash-card teaching apparatus looking from left to right at FIGS. 1 and 2;

FIG. 4 is a front elevation of the flash-card teaching apparatus; and

FIG. 5 is a rear elevation of the flash-card teaching apparatus.

I claim:

The ornamental design for a flash-card teaching apparatus, as shown.
